UNITED STATES PATENT OFFICE.

WALDO G. GERNANDT, OF CHICAGO, ILLINOIS, ASSIGNOR TO GERNANDT MOTOR CORPORATION, OF CHICAGO, ILLINOIS, A CORPORATION OF ILLINOIS.

HIGH-COMPRESSION QUICK-COMBUSTION ENGINE.

1,359,498.

Specification of Letters Patent. Patented Nov. 23, 1920.

Application filed June 8, 1918. Serial No. 239,028.

To all whom it may concern:

Be it known that I, WALDO G. GERNANDT, a citizen of the United States, and a resident of Chicago, in the county of Cook and 5 State of Illinois, have invented certain new and useful Improvements in High-Compression Quick-Combustion Engines, of which the following, when taken in connection with the drawings accompanying and 10 forming a part hereof, is a full and complete specification.

This invention relates to a high pressure quick combustion engine.

The objects of the invention are to obtain 15 a construction which, when applied to a quick combustion engine of the named type is effective in operation, economical in construction and not liable to break or get out of order, and which is adapted to make 20 use of light or heavy liquid hydro-carbon for fuel.

A further object of the invention is to obtain 25 a high compression engine which does not require any considerable change from the construction of ordinary, or low pressure quick combustion engines, other than the substitution of a head embodying the principal features of this invention for the head now in use; it being understood 30 that in a high compression engine of the types named no ignition plug is required.

A further object is to obtain an engine 35 of the high compression type wherein the "work" done is varied by corresponding variation in the quantity of fuel supplied.

In quick combustion engines of the high compression type made by me I have found it difficult to prevent leakage of gas under great pressure when compression rings are 40 relied on, particularly in making use of small auxiliary pistons to one side of the engine pistons to obtain and maintain a high pressure outside of the combustion chamber, and a very essential part of this 45 invention is embodied in the construction which obviates the use of spring rings auxiliary to the ordinary piston rings.

Additional objects are hereinafter set forth and disclosed by the claims.

50 In the drawings referred to a construction embodying the novel features of the invention is exhibited, applied to the cylinders of a two cycle engine, and in said drawings;—

55 Figure 1, represents a vertical sectional

view of the several movable parts illustrated in proper relative position for ignition of a compressed charge in the combustion chamber of the engine cylinder.

Fig. 2, represents a like view, the several 60 parts which are illustrated being in proper relative position subsequent to ignition of said charge in the combustion chamber and

Fig. 3, a like view, the several parts which are illustrated being in proper relative and 65 normal position during the greater part of the travel of the piston of the engine.

Fig. 4 is an elevation showing one end 70 of the cam shaft and adjacent parts actuated thereby.

A reference character applied to designate a given part indicates said part throughout the several figures of the drawings, wherever the same appears.

1, represents the piston of a two cycle engine, 1^a the cylinder, 2 the piston rings and 2^a the connecting rod. 3 represents the combined compression and combustion chamber of cylinder 1^a and 3^a the head of 75 said cylinder which forms one end of said chamber 3, and in which head the several parts about to be described are positioned.

An auxiliary compression chamber in head 3^a is designated by the numeral 4. 5 represents a longitudinally movable plunger one end whereof forms a movable wall to compression chamber 4, and 6 represents a shoulder on the plunger 5, which forms a valve adapted to co-act with valve seat 7. 8, represents an ordinary packing gland. 90

9, represents a lever which is illustrated as pivoted on pin 10. 11 indicates the upper end of a rod which is illustrated as attached by pin 12 to lever 9. Rod 11 is adapted to be actuated by a cam on the cam shaft 95 of the engine and moved longitudinally thereby. Lever 9 is illustrated as connected to plunger 5, by means of shoulders 13, 14 and the intervening spring 15. By means of the connection 9 to 15 inclusive the plunger is forced downward to a determined position by lever 9, and is raised by said lever to close the valve 6, on seat 7; the spring 15 being adjusted to be under tension when said valve is seated. A recess 105

extending axially from the lower end of plunger 5 is indicated by the broken lines 16 and said recess forms a passageway which at its upper end is illustrated as connecting by means of radial apertures, which 110

- are numbered 17, with the annular groove designated by the numeral 18. 19 represents a fuel depository in member 19^a which at its lower end is provided with the 5 radially extending apertures 20 communicating with the combustion chamber 3. Fuel is supplied to the depository 19, through passageway 21 in member 21^a, and said passageway is provided with the check 10 ball 22 at its lower end. 23 represents a pin to hold the ball adjacent to its seat. 24, 25 represent coaxial passageways, respectively connecting with fuel depository 19, and annular groove 18 on plunger 5. These passageways are arranged to be obstructed by 15 valve 26 in member 26^a when said valve is closed on its seat 27. 28 represents the stem of valve 26 and 29 a gland or packing for said stem.
- 20 The normal position of valve 26 is illustrated in Fig. 3 of the drawings, it being closed during the movement of the piston 1 from the position in which it is illustrated in said Fig. 3 during the downward travel 25 of said piston and its return to its said indicated position.

29^a is a union by means of which the fuel supply pipe 30 is attached to the member 21^a. 31 represents packing material which 30 is interposed between members 21^a and 19^a; 19^a and 3^a; 26^a and 3^a; and between head 3^a and the end of cylinder 1^a.

32 designates one of the bolts by means of which cylinder 1^a and head 3^a are joined.

33 indicates water space in cylinder 1^a and 34 water space in head 3^a.

The plunger 5 and valve 26, as hereinbefore stated, are normally in position so that said valve 26 and valve 6 are seated; and 40 at such time no gas however great its pressure may be, can flow lengthwise of the plunger through gland 8 or in either direction between passageways 24 and 25, it being observed that the adjacent opened ends 45 of said passageways are positioned in seat 27 of said valve 26.

In Fig. 4, the crank shaft is indicated by characters 35, the crank by 35^a, and a gear wheel which is rigidly secured to the crank 55 shaft by 36. 37 represents a gear wheel which intermeshes with gear wheel 36, and which is rigidly secured on rotatably mounted cam shaft 38. 38^a and 39 represent cams rigidly secured on shaft 38. Rod 11 is actuated by cam 38^a; and 40 represents a like rod which is actuated by cam 39. 41 represents a bearing adjacent to the lower ends of rods 11 and 40, in which 60 bearings said rods are longitudinally movable. 42 represents a pivotal pin which connects rod 40 to lever 43 near one end of said lever. The other end of lever 43 is arranged to force the valve stem 28 down as said lever is turned on its fulcrum 44 by 65 cam 39. 45 represents a spring which abuts

at its upper end on annular flange or collar 46. Collar 46 is rigidly secured on valve stem 28, and said spring 45 yieldingly holds the valve 26 seated at all times when not actuated as above described by cam 39. 70

The operation of the several parts or elements described is as follows:—

The timed relation of said parts and elements to piston 1 is such that immediately prior to ignition of the contents of combustion chamber 3 plunger 5 and valve 26 rapidly descends. The products of combustion in compression chamber 4 are thus put under greater pressure than is the compressed air in said combustion chamber, and hence the contents of said compression chamber are forced through recess 16, apertures 17, annular groove 18, passageways 25 and 24 fuel depository 19 and radial passageways 20, (being discharged with considerable force), into the contents of said combustion chamber. In the discharge, as last above set out, of the compressed products of combustion from compression chamber 4, fuel contained in fuel chamber 19 (said fuel being at the lower end thereof and obstructing passageways 20), will be forced through said passageways in advance of said discharge of said products of combustion. 85 90 95

The last above recited action occurs when the several parts and members are in substantially the position, which is illustrated in Fig. 1, of the drawings.

Piston 1 will, upon the ignition of the 100 contents of combustion chamber 3, descend and on or before said piston has traveled downward with the upper end thereof in the position which is illustrated in Fig. 2, of the drawings, plunger 5 will be raised to 105 seat valves 6. At this time the lower end of said plunger is above the passageway 25 and the ignition contents of compression chamber 3 will flow therefrom through passageways 20, fuel chamber 19, passageways 110 24, and 25 into said compression chamber 4.

Piston 1, continuing its travel, will descend to and beyond the position thereof which is indicated in Fig. 3, and on or before the upper end of said piston is in said 115 position the valve 26 is seated, thus obstructing communication between passageways 24 and 25.

At this time the pressure in combustion chamber 3 and compression chamber 4 is 120 substantially the same, and valve 6 and 26 remaining seated the said contents of compression chamber 4 are sealed therein and will so remain during the remainder of the travel of the piston 1 on its working stroke 125 and during its return, (on the compression stroke thereof in the two cycle engine illustrated), until said piston is near to or in the position in which it is illustrated in Fig. 1, at which time plunger 5 and valve 26 130

move downward rapidly giving additional pressure to the contents of said compression chamber 4 and removing the obstruction (valve 26) from the several recited passage-
6 ways communicating with said compression and combustion chambers. During the time the valve 26 is seated, the pressure in fuel chamber 19 becomes lessened sufficiently to permit fuel to flow from passageway 21
10 into said fuel chamber 19, where by gravity it will drop to the bottom of said chamber and seal passageway 20, said passageways 20 being of small diameter and sufficiently long to prevent the flow of said fuel there-
15 from into the combustion chamber until forced therethrough by the high pressure obtaining in said compression chamber upon the establishing of communication between said compression chamber 4 and said fuel chamber as hereinbefore recited.
20

The above recited cycles are repeated so long as fuel is supplied through conduit 30 to passageway 21 and fuel chamber 19, and the quantity of fuel so supplied determines
25 the "work" of the engine.

I claim:

1. In a quick combustion engine provided with a combustion chamber, a cylinder head provided with a fuel depository in continuous communication with said combustion chamber, a well and a passage way communicable with said depository and with said well, in combination with means, comprising a valve seat and a normally seated co-
30 acting valve, to obstruct said passage way, a plunger in said well, and means to retract and to advance said plunger, said plunger normally in a retracted position, and said valve and plunger timed to establish communication between said depository and well, said plunger being in substantially its advanced position, and, said plunger being in its normal position, to trap products of combustion flowing from said combustion
35 chamber through said fuel depository at substantially ignition pressure.
40

2. In a quick combustion engine provided with a combustion chamber, a cylinder head provided with a well, a fuel depository in continuous communication with said combustion chamber, and a passage way communicating with said well and with said depository, in combination with a valve and a co-acting valve seat, said valve normally seated to obstruct said passage way, a longitudinally movable plunger in said well, and means to advance and to retract said plunger, said plunger provided with a stop, a co-acting seat to said stop, and said plunger normally in a retracted position to seat said stop.
50

3. In a quick combustion engine provided with a combustion chamber, a cylinder head provided with a well, a fuel depository in continuous communication with said com-

bustion chamber and a passage way communicating with said well and with said depository, in combination with a valve and a co-acting seat, said valve normally seated to obstruct said passage way, a longitudinally movable plunger in said well, said plunger provided with a stop, a seat co-acting with said stop, and said plunger normally in a retracted position to seat said stop, a lever arranged to force said plunger to an advanced position and to retract said plunger to its normal position, and a yielding member interposed between said plunger and lever and arranged to be under pressure when said plunger is in its normal position.
70
75
80

4. In a quick combustion engine provided with a combustion chamber, a well, a plunger, a stop on said plunger and a co-acting seat to said stop, said plunger normally in a retracted position to seat said stop and longitudinally movable in said well to an advanced position, a fuel depository in continuous communication with said combustion chamber and a passage way communicating with said well and with said depository, means to obstruct said passage way and means to remove said obstruction concurrently with said plunger being in an advanced position and to maintain said removal to trap, said plunger being in said normal position, products of combustion at substantially ignition pressure, all combined as set forth.
85
90
95

5. In a quick combustion engine provided with a combustion chamber, means to supply fuel to said chamber, said means comprising a fuel depository in continuous communication with said chamber and adapted to alternately receive fuel from a fuel supply and products of combustion from said chamber, means to trap products of combustion flowing from said chamber into said depository at substantially ignition pressure and means to return said trapped products under additional pressure to said chamber
100 from said depository, said means to trap and return said products of combustion comprising said depository, a well, a plunger in said well, a passage way communicating with said depository and with said well and arranged to form an inlet to and an outlet from said well, means to obstruct said passage way and means to remove said obstruction.
105
110
115

6. In a quick combustion engine provided with a combustion chamber, a well, a plunger in said well, normally stationary in a retracted position and longitudinally movable to an advanced position and return, a stop on said plunger and a co-acting seat therefor, said stop arranged to be seated when said plunger is in said normal position, in combination with a fuel depository in continuous communication with said chamber, a passage way in continuous com-
120
125
130

munication with said fuel depository and, said plunger being in said normal position, with said well, a co-acting valve and valve seat, said valve being normally seated 5 to obstruct said passage way and movable to be unseated concurrently with said plunger approaching its advanced position and to trap products of combustion at substantially ignition pressure on said plunger being in 10 said normal position, and means to establish communication between said well and said passage way on said approach of said plunger to said advanced position.

7. In a quick combustion engine, provided 15 with a combustion chamber, means to supply fuel to said chamber, said means comprising a fuel depository in continuous communication with said chamber and adapted to receive products of combustion from said 20 chamber, means to trap products of combustion from said combustion chamber flowing through said depository, said trapped products being at substantially ignition pressure, and said means comprising a well, 25 a passageway communicating with said depository and said well, and means to seal said well, a passageway and depository arranged to discharge the contents of said well into said combustion chamber.

30 8. In a quick combustion engine, provided with a combustion chamber, means to supply fuel to said chamber, said means comprising a fuel depository in continuous communication with said chamber and adapted to receive products of combustion from said 35 chamber, means to trap products of combustion from said combustion chamber flowing through said depository, said trapped products being at substantially ignition pressure, 40 and said means comprising a well, a passageway communicating with said depository and said well, and means to seal said well, means to break said seal and apply additional pressure to the products of combustion in said well, said passageway and de-

pository arranged to discharge the contents of said well into said combustion chamber.

9. In a quick combustion engine provided with a combustion chamber, a cylindrical well, a plunger in said well, normally stationary in a retracted position and longitudinally movable to an advanced and to said retracted position, an annular shoulder on said plunger arranged to form a stop, a co-acting seat to said stop to form a seal, a lever, a spring interposed between said lever and said plunger, said lever arranged to force said plunger to said advanced position and to retract said plunger to said normal position, and said spring arranged to permit said lever to continue its movement, the said plunger being in said normal position and said stop seated, in combination with a passageway communicating with said combustion chamber and with said well when said plunger is in said normal position.

10. In a quick combustion engine provided with a combustion chamber, a cylindrical well, a plunger in said well, an annular stop on said plunger, a seat co-acting with said stop to form a seal, normally stationary in a retracted position and longitudinally movable to an advanced and to said retracted position, a lever, a spring interposed between said lever and said plunger, said lever arranged to force said plunger to said advanced and to retract said plunger to said normal position, and said spring arranged to permit said lever to continue its movement, the said plunger being in said normal position and said stop seated, in combination with a passageway communicating with said combustion chamber and with said well when said plunger is in its normal position, a co-acting valve seat and valve, said valve being normally seated to close said passageway.

WALDO G. GERNANDT.
In presence of—
CHARLES TURNER BROWN.
